To all whom it may concern:

Be it known that I, Solomon E. Koplar, a citizen of the United States, residing in Chicago, county of Cook, and State of Illinois, have invented a new, original, and ornamental Design for a Clock, of which the following is a specification, reference being had to the accompanying drawing, forming part thereof.

Fig. 1 is a front perspective view of a clock, showing my new design; and

Fig. 2 is a rear elevation of the clock.

I claim:

The ornamental design for a clock, substantially as shown.

SOLOMON E. KOPLAR.
